(57) **CLAIM**

The ornamental design for a charging station, as shown and described.

DESCRIPTION

FIG. 1 is a top front perspective view of a charging station showing my new design;

FIG. 2 is a front elevation view thereof;

FIG. 3 is a rear elevation view thereof;

FIG. 4 is a top elevation view thereof;

FIG. 5 is a bottom elevation view thereof; and,

FIG. 6 is a right elevation view thereof, with the left elevation view being a mirror image thereof.

The broken lines shown in the drawings illustrate portions of the charging station that form no part of the claimed design. The charging station is shown with a symbolic break in its length. The appearance of any portion of the article between the break lines forms no part of the claimed design.
